PROJECTILE-ACCELERATING MECHANISM
FOR FIREARMS

Everett N. Stanley, Casper, Wyo.

Application September 21, 1951, Serial No. 247,604

9 Claims. (Cl. 89—8)

1

This invention relates to the construction of firearms. More particularly, the invention has reference to means adapted to be incorporated in a weapon of conventional design, and operative to increase the speed and range of a projectile discharged from said weapon.

Efforts have heretofore been made to increase the velocity of a bullet, and most of these efforts have been directed to the addition of powder to the original charge contained in the cartridge case. However, it is well appreciated among those skilled in the art that in direct proportion to any increases in the original powder charge, there is a dangerous increase in internal pressures occurring within the firearm on discharge of the projectile. Pressures mount rapidly, and in some instances are critical to one-half of one grain in weight. This is due to the fact that the bullet is a dead weight when the cartridge is fired, the pressure peak being reached before the bullet travels one inch along the barrel of a conventional rifle.

Since the pressure peak is reached within one inch of the starting point of the projectile, it is obvious that the pressure will decrease rapidly as the bullet continues down the barrel, the pressure decreasing progressively as the space behind the bullet increases with the forward travel thereof. For example, after the bullet has traveled slightly more than the length of the cartridge, the pressure peak will in most cases have fallen to less than half its maximum.

In view of the above, I propose, in carrying out the main object of the present invention, to provide a supplementary powder charge spaced from the starting point of the projectile a distance slightly more than the length of the cartridge, so as to exert a surge of pressure against the moving bullet, after the conventionally sized, safe charge has overcome the initial inertia of said bullet, and has started the bullet along the barrel.

A further important object is to provide for automatic replenishment of the supplementary charge, responsive to the firing of each projectile.

Another important object is to provide a construction, in a mechanism of the type referred to, wherein the gases released by explosion of the conventional charge contained in the cartridge will act within said mechanism in such a manner as to be effective not only for exploding the supplementary charge, but also for effecting the automatic replenishment of the supplementary charge, ready for the firing of the next projectile.

A further important object is to provide safety

2

means associated with the automatic charge-replenishing means in such a manner as to effect, automatically, the discharge of gases leaking past the second-named means, to atmosphere.

5 A still further object is to provide for adjustment of the supplementary powder charge as to the quantity thereof.

Another important object is to provide a powder magazine adapted to hold a quantity of powder for replenishment of the supplementary projectile-accelerating charge, in which the natural recoil of the firearm will be additive to a spring means contained within the magazine, so as to continuously maintain the powder in the magazine in proper position for movement of a predetermined portion of said powder into the supplementary charge chamber.

I am aware that it is not broadly new, in firearm construction, to provide a supplementary powder charge, positioned in advance of the initial position of the projectile, that is ignited by the gases released by explosion of the original powder charge, to add velocity to the projectile as it moves out of the barrel. However, to my

20 knowledge, no mechanism previously developed along this line has included a means for automatically replenishing the supplementary powder charge. All such devices of which I have knowledge have been adapted for use with single-shot weapons only, and have required manual

25 replenishment of the supplementary charge, in a time-consuming operation, each time the firearm is to be discharged. The present invention, however, is adapted for use not only with single-shot weapons, but also with automatic or semi-automatic weapons, replenishment being necessary only upon exhaustion of the magazine, which magazine is so designed as to be of any size desired.

Other objects will appear from the following 30 description, the claims appended thereto, and from the annexed drawings, in which like reference characters designate like parts throughout the several views, and wherein:

Figure 1 is a longitudinal sectional view 35 through a firearm, in which portions of said firearm are broken away, and through a projectile-accelerating mechanism formed in accordance with the present invention, and operatively associated with said firearm;

50 Figure 2 is a transverse sectional view taken on line 2—2 of Figure 1;

Figure 3 is a top plan view of said firearm and mechanism, in which portions of the firearm are broken away;

55 Figure 4 is a longitudinal sectional view

through the mechanism constituting the present invention, taken substantially on line 4—4 of Figure 3; and

Figure 5 is a transverse sectional view through said mechanism, taken substantially on line 5—5 of Figure 1.

Referring to the drawings in detail, by way of example the device constituting the present invention has been illustrated in association with a rifle generally designated 6, said rifle being of generally conventional construction. However, it is believed important to note at this point that the device is capable of application to rifles of any caliber, from the smallest up to and including the largest artillery and naval rifles and may be readily applied also, to guns other than rifles. Accordingly, except as necessarily restricted by the scope of the appended claims, the term "gun" as used hereinafter is intended to apply generically to all types of weapons in which a projectile is discharged from a barrel by explosion of a powder charge.

The gun 6 illustrated in the drawings includes a barrel 8, at one end of which is provided a breech mechanism 10 including a firing pin 12 adapted to detonate a powder charge contained within the cartridge 14, that includes a projectile 16. The powder charge contained within the cartridge 14 will be hereafter termed the "original charge," to distinguish it readily from the supplementary charge to be described herein.

The barrel 8 is provided with the usual longitudinal bore 18, through which the projectile 16 moves upon detonation of the original charge.

In accordance with the present invention, I apply to the barrel 8, slightly in advance of the initial position of the projectile 16, a clamp 20 (Figure 2) of inverted U-shaped formation, having depending, parallel, threaded arms 22 that extend through smooth walled openings 24 formed in opposite ends of a clamp plate 26, that is arranged transversely of and below the barrel 8. Nuts 28 are threaded upon the arms 22, for urging the clamp plate in the direction of the barrel.

The barrel 8 is formed with a small-diameter outlet passage 30 disposed transversely of the barrel, said passage communicating at one end with the bore 18 of the barrel, and being formed at its other end with a counterbore 32 complementary to one end of an enlargement 34, that is integrally or otherwise formed upon the inlet end of a connecting tube 36 underlying and extending longitudinally of the barrel 8, as readily noted from Figure 1.

The clamp plate 26 has a center opening formed complementary to the other end of the enlargement 34 so that threading of the nuts 28 against the clamp plate 26 is operative to connect the inlet end of the connecting tube 36 to the barrel 8, in communication with the outlet passage 30 of the barrel.

Adjacent its outlet end, the connecting tube 36 is formed with a lateral extension 40 provided with an enlargement 42 engaging in a complementarily formed recess in a block generally designated 44. The block 44 (see Figure 5) is secured to the barrel 8 so as to depend therefrom, the connection of the block to the barrel being obtained through the provision of a barrel-receiving opening 45 formed in the upper end of the block, adjacent one side thereof, a set screw 47 (Figure 1) being threaded through the wall of said opening against the surface of the barrel.

To effect a rigid connection between the connecting tube and the block 44, I provide a clamp plate 46 having an opening receiving the lateral extension 40 of the connecting tube, and having smooth walled end openings receiving screws 48, that are threadable into suitably located threaded recesses formed in the block 44.

Formed in the block 44 and opening upwardly from the bottom surface of the block contiguous to that side thereof opposite the side receiving the barrel 8, is a counterbore 50. The counterbore 50 extends approximately half the length of the block 44, and at its lower end is threaded to receive a plug 52. An inlet passage 54 of small diameter communicates at one end with the outlet end of the connecting tube 36, and at its other end is in communication with the counterbore 50 immediately above the plug 52, said inlet passage being formed in and extending longitudinally of the block 44.

A piston 56 is mounted in the counterbore 50, to slide longitudinally therein and on one face thereof, is formed with a spacer lug 57, that engages the plug 52 in the normal position of the piston 56 (see Figure 4), so as to define between the piston and plug an inlet chamber 59 into which gases formed by explosion of the original charge may pass.

A slide valve 58, that is reduced in diameter relative to the diameter of the counterbore and piston, is formed upon the opposite face of the piston, and is disposed longitudinally of the counterbore. The free end of the slide valve is retained continuously within a powder inlet passage 60 formed as a reduced-diameter axial extension of the counterbore. Thus, communication between the powder inlet passage and the counterbore is prevented at all times by the slide valve.

A spring 62 surrounds the slide valve, said spring abutting at one end against the shoulder defined at the inner end of the counterbore, and abutting at its other end against the piston 56. The spring 62 is under continuous compression, so as to continuously and yieldably bias the piston 56 to the normal position thereof illustrated in Figure 4.

Formed upon the slide valve 58, adjacent the free end thereof, is an annular groove 64. When the piston 56 is forced upwardly within the counterbore 50, against the action of the spring 62, the groove 64 will register with an upper relief passage 66 (Figures 3 and 5) formed in the block 44, and communicating between the powder inlet passage 60 and the atmosphere. When the piston is in its normal position, the groove 64 registers with a second relief passage 68, communicating between the counterbore and atmosphere. The relief passage or port 66 is for exhausting to atmosphere any gas that may leak upwardly past the piston 56 from the chamber 59, to prevent said gas from leaking into the powder magazine embodied in the invention, which will be described hereinafter. The port 68 is for the purpose of preventing leakage of gases into the supplementary charge cylinder past the slide valve, which cylinder also will be described in detail hereinafter.

The powder magazine has been designated 70, and is formed as an elongated tubular member disposed longitudinally of and in parallelism with the barrel 8. At one end, the magazine is externally threaded to receive a closure cap 72, while at the other end the magazine is provided with a rotatable cap 74. The cap 74 is adapted

to be partially rotated in opposite directions upon its associated end of the magazine 70, and to this end, a screw 76 (Figures 3 and 4) is threaded through the flange of the cap 74, and extends into a transverse slot 78 formed in the wall of the magazine 70, so as to limit rotatable movement of the cap 74 in opposite directions.

Secured to the cap 74 and extending longitudinally of and within the magazine 70, is a main valve 80. On rotation of the cap 74 to one position, designated "off" in Figure 3, the main valve 80 is positioned to close off communication between the magazine 70 and the powder inlet passage 60. On partial rotation of the cap 74 to its opposite extreme position, designated "on" in Figure 3, the main valve is adjusted within the cylinder to open communication between the magazine and the powder inlet passage. In this way, the user of the mechanism is enabled to shut off the mechanism entirely, whenever it is desired to discharge the weapon without the supplementary charge.

To secure the magazine 70 fixedly to the block 44, I provide a set screw 82 (Figure 5) threadable through registering openings formed in the block and magazine respectively.

Slidable within and longitudinally of the powder magazine 70 is a piston 84, which is urged continuously in the direction of the outlet passage 60 by a coil spring 86 interposed between said piston and the cap 72.

As seen from Figure 5, a communicating bore 88 is formed in the block 44, being disposed transversely of the block so as to communicate at one end with the passage 60 and at its other end with a supplementary charge chamber 90. The chamber 90 is formed as an elongated bore opening from the bottom surface of the block 44, and extending in parallel relation to the counterbore 50 and the passage 60, said chamber opening at 30 its other end into a supplementary charge outlet passage 94, that is formed in the barrel 8, extending obliquely into communication with the bore 18 of the barrel.

A threaded plug 92 engages internal threads formed in the lower end of the supplementary charge chamber 90. The plug 92 may be threaded to any position within said chamber 90, so as to regulate the size of the chamber, and hence the size of the supplementary charge.

To permit the drilling of the communicating bore 88, an opening 96 is extended inwardly from the exterior surface of the block 44, said opening being arranged in coaxial alignment with the communicating bore, and being internally threaded to receive a closure plug 98.

Considering now the operation of the mechanism, on explosion of the original charge, the projectile 16 will move past the outlet passage 30 of the rifle barrel. As a result, the gases released by explosion of the original charge will pass through the connecting tube 36, into the chamber 59.

The pressure of the gases forced into the chamber 59 is operative to force the piston and slide valve upwardly from their normal positions, so that the slide valve closes off communication between the powder inlet passage 60 and the communicating bore 88.

The projectile, meanwhile, will travel further along the bore 18 of the barrel 8, so as to pass over the passage 94. Gases released by explosion of the original charge will, accordingly, pass into said passage 94 and will ignite the powder charge contained within the supplementary chamber 90.

The ignited supplementary charge, as a result, will exert its force through the bore 94 against the rear of the projectile, before said projectile passes fully out of the barrel 8. In this way, the supplementary charge is effective to make up the loss of pressure referred to in the objects stated hereinabove, which loss of pressure increases as the distance between the projectile and the initial position of the cartridge increases.

As the projectile passes out of the barrel, all gas pressures within the barrel, supplementary charge chamber 90, and gas inlet chamber 59, are relieved immediately. As a result, spring 62, tending to expand, biases the piston 56 towards normal position, opening communication automatically between the magazine 70, powder inlet passage 60, communicating bore 88, and supplementary charge chamber 90, as a result of which a new supplementary powder charge is forced into the supplementary charge chamber 90.

In this way, the supplementary charge is replenished automatically, so that on the next discharge of the weapon, acceleration of the projectile will obtain once again. This action will continue as long as there is a supply of powder within the magazine 70.

It may be noted that the forcing of the supplementary charge into the chamber 90 is obtained by the tendency of the spring 86 to expand, which continuously exerts pressure against the piston 84 in the direction of the powder inlet passage 60. In this connection, the natural recoil of the gun will be additive to the pressure of the spring 86 to assure efficient operation of the charge-replenishing means.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. A projectile-accelerating mechanism for guns comprising, in combination with a gun barrel, a supplementary charge chamber adapted to contain a predetermined quantity of an explosive material and communicating with the barrel for ignition of said material by an original explosive charge detonated within the barrel; a magazine containing a supply of said material and normally communicating with the supplementary charge chamber; means on the magazine adapted to force said material into said chamber whenever the chamber and magazine are in communication; and a valve arranged for actuation by the detonated original charge to a position in which it closes communication between the supplementary charge chamber and magazine.

2. A projectile-accelerating mechanism for guns comprising, in combination with a gun barrel having longitudinally spaced passages opening upon the bore thereof, a supplementary charge chamber adapted to contain a predetermined quantity of an explosive material and communicating continuously with one of said passages for ignition of said material by an original explosive charge detonated within the bar-

rel; a magazine containing a supply of said material and normally communicating with the supplementary charge chamber; means on the magazine adapted to force said material into said chamber whenever the chamber and magazine are in communication; a valve arranged for actuation by the detonated original charge to a position in which it closes communication between the supplementary charge chamber and magazine; and means extending between the other passage of the barrel and said valve and adapted for transmitting to the valve gas pressures resulting from detonation of the original charge, for actuation of the valve to said position.

3. A projectile-accelerating mechanism for guns, comprising, in combination with a gun barrel having a pair of passages opening upon the bore thereof and spaced different distances from the breech end of the barrel, a supplementary charge chamber adapted to contain a predetermined quantity of an explosive material and communicating continuously with that passage remote from the breech end of the barrel for ignition of said material by an original explosive charge detonated within the barrel; a magazine containing a supply of said material and normally communicating with the supplementary charge chamber; means on the magazine adapted to force said material into said chamber whenever the chamber and magazine are in communication; a valve arranged for actuation by the detonated original charge to a position in which it closes communication between the supplementary charge chamber and the magazine; and means extending between the passage nearer the breech end of the barrel and said valve and adapted for transmitting to the valve gas pressures resulting from detonation of the original charge, for actuation of the valve to said position.

4. A projectile-accelerating mechanism for guns comprising, in combination with a gun barrel having a pair of passages opening upon the bore thereof and spaced different distances from the breech end of the barrel, a supplementary charge chamber adapted to contain a predetermined quantity of an explosive material and communicating continuously with that passage remote from the breech end of the barrel for ignition of said material by an original explosive charge detonated within the barrel; a tubular magazine containing a supply of said material and normally communicating with the supplementary charge chamber; a spring-biased piston in the magazine adapted to exert pressure longitudinally of the magazine to force said material into said chamber whenever the chamber and magazine are in communication; a valve arranged for actuation by the detonated original charge to a position in which it closes communication between the supplementary charge chamber and magazine; and means extending between that passage nearer the breech end of the barrel and said valve and adapted for transmitting to the valve gas pressures resulting from detonation of the original charge, for actuation of the valve to said position.

5. A projectile-accelerating mechanism for guns, comprising, in combination with a gun barrel having a pair of passages opening upon the bore thereof and spaced different distances from the breech end of the barrel, a supplementary charge chamber adapted to contain a predetermined quantity of an explosive material and communicating continuously with that passage remote from the breech end of the barrel for igni-

tion of said material by an original explosive charge detonated within the barrel; a tubular magazine extending longitudinally of the barrel and adapted to contain a supply of said material, said magazine normally communicating with the supplementary charge chamber; a piston slidable in the magazine; a spring within the magazine and exerting pressure against the piston in the direction of the muzzle end of the barrel, for coaction with gun recoil pressures to force material into said chamber whenever the chamber and magazine are in communication; a valve arranged for actuation by the detonated original charge to a position in which it closes communication between the supplementary charge chamber and magazine; and means extending between that passage nearer the breech end of the barrel and said valve and adapted for transmitting to the valve gas pressures resulting from detonation of the original charge, for actuation of the valve to said position.

6. A projectile-accelerating mechanism for guns comprising, in combination with a gun barrel having a pair of passages opening upon the bore thereof and spaced different distances from the breech end of the barrel, a block having a supplementary charge chamber adapted to contain a predetermined quantity of an explosive material, said chamber communicating continuously with that passage remote from the breech end of the barrel for ignition of said material by an original explosive charge detonated within the barrel; a tubular magazine mounted on the block to extend longitudinally of the barrel and adapted to contain a supply of said material, said magazine normally communicating with the supplementary charge chamber; a piston slidable in the magazine; a spring within the magazine and exerting pressure against the piston in the direction of the muzzle end of the barrel for coaction with gun recoil pressures to force material into said chamber whenever the chamber and magazine are in communication; a valve mounted in the block and arranged for actuation by the detonated original charge to a position in which it closes communication between the supplementary charge chamber and the magazine; and means extending between that passage nearer the breech end of the barrel and said block and adapted for transmitting to the valve gas pressures resulting from detonation of the original charge, for actuation of the valve to said position.

7. A projectile-accelerating mechanism for guns comprising, in combination with a gun barrel having a pair of passages opening upon the bore thereof and spaced different distances from the breech end of the barrel, a block having a supplementary charge chamber adapted to contain a predetermined quantity of an explosive material, said chamber communicating continuously with that passage remote from the breech end of the barrel for ignition of said material by an original explosive charge detonated within the barrel; a magazine carried by the block and normally communicating with the supplementary charge chamber; means in the magazine adapted to exert a continuous yielding pressure upon the material contained therein tending to force said material into the supplementary charge chamber; a valve mounted in the block and arranged for actuation by the detonated original charge to a position in which it closes communication between the supplementary charge chamber and magazine; and means extending between that

passage nearer the breech end of the barrel and said block and adapted for transmitting to the valve gas pressures resulting from detonation of the original charge, for actuation of the valve to said position.

8. A projectile-accelerating mechanism for guns comprising, in combination with a gun barrel having a pair of passages opening upon the bore thereof and spaced different distances from the breech end of the barrel, a block connected to said barrel and having a gas inlet chamber, the block having a supplementary charge chamber adapted to contain a predetermined quantity of an explosive material and communicating continuously with that passage remote from the breech end of the barrel for ignition of said material by an original explosive charge detonated within the barrel; a magazine carried by the block and normally communicating with the supplementary charge chamber; means in the magazine adapted to exert a continuous yielding pressure upon the material contained therein tending to force said material into the supplementary charge chamber; a valve slidable in the block at one end of the gas inlet chamber and arranged for actuation by the detonated original charge to a position in which it closes communication between the supplementary charge chamber and magazine; and means extending between that passage nearer the breech end of the barrel and the gas inlet chamber and adapted for transmitting to the gas inlet chamber gases resulting from detonation of the original charge for actuation of the valve to said position.

9. A projectile-accelerating mechanism for guns comprising, in combination with a gun barrel having a pair of passages opening upon the bore thereof and spaced different distances from the breech end of the barrel, a block connected to said barrel and having a gas inlet chamber,

the block having a supplementary charge chamber adapted to contain a predetermined quantity of an explosive material and communicating continuously with that passage remote from the breech end of the barrel, for ignition of said material by an original explosive charge detonated within the barrel, the block having a supplementary charge inlet passage formed as an extension of the gas inlet chamber and a bore communicating between the supplementary charge chamber and said supplementary charge inlet passage, a magazine carried by the block in communication with the supplementary charge inlet passage; means in the magazine adapted to exert a continuous yielding pressure upon the material contained therein tending to force said material into the supplementary charge chamber through the supplementary charge inlet passage and said communicating bore; a valve slid- 15 able in the supplementary charge inlet passage at one end of the gas inlet chamber and ar- ranged for actuation by the detonated original charge to a position in which it closes communi- 20 cation between the supplementary charge inlet passage and said communicating bore, and means extending between that passage of the 25 barrel nearer the breech end thereof and the gas inlet chamber and adapted for transmitting to the gas inlet chamber gases resulting from 30 detonation of the original charge, for actuation of the valve to said position.
